*Fig. 5**Fig. 6**Fig. 7*

FIG. 1 is perspective view of an aerosol actuating button protector showing my new design, an aerosol actuating button being shown in broken lines for illustrative purpose only;

FIG. 2 is an enlarged top plan view;

FIG. 3 is a front elevation;

FIG. 4 is a side elevation;

FIG. 5 is a rear elevation;

FIG. 6 is a fragmentary sectional view taken on the line 6—6 of FIG. 2; and

FIG. 7 is a fragmentary sectional view taken on the line 7—7 of FIG. 2.

I claim:

The ornamental design for an aerosol actuating button protector, as shown and described.
